UNITED STATES PATENT OFFICE

DAVID H. McCLELLAND, OF CHICAGO, ILLINOIS.

NAIL-MAKING MACHINE.

1,217,194.

Specification of Letters Patent. Patented Feb. 27, 1917.

Application filed May 27, 1912. Serial No. 700,069.

To all whom it may concern:

Be it known that I, DAVID H. McCLELLAND, a citizen of the United States, residing in Chicago, in the State of Illinois, have invented new and useful Improvements in Nail-Making Machines, of which the following is a specification.

My invention relates more particularly to that class of machine which may be used to make a nail having two heads, and make it from one piece of material. Further objects of this invention are to provide a machine of extreme simplicity of parts and of such a combination of parts and members that it will impart great pressure upon the head-forming dies as compared with the amount of power transmitted to the machine.

With the above and other objects in view, this invention consists of a novel provision, construction, association and relative arrangement of parts and members as hereinafter described and shown in the accompanying drawings.

In the drawings:

Fig. 1 is a side elevation with portions broken away for clearness of illustration.

Fig. 2 is an enlarged portion of the feed clutch.

Fig. 3 is a portion of the feed clutch and die carrier in the opposite position from those shown in Fig. 1.

Fig. 4 is a top plan view.

Fig. 5 is a top plan view with portions removed and movable parts in the opposite position from those shown in Fig. 4.

Fig. 6 is an enlarged view of loose and tight pulley and crank disk removed from the machine.

Fig. 7 is an enlarged sectional view taken on line $\alpha-\alpha$ of Fig. 1.

Fig. 8 is an enlarged view of the die carrier removed from the machine.

Fig. 9 is a sectional view taken on line $y-y$ of Fig. 8.

Fig. 10 is a view of one of the rocker arms removed from the machine, with part broken away exposing the grip die and shear knife.

Similar reference characters refer to similar parts and members throughout the several views.

In detail the numeral 1 refers to the end of a coil of wire (coil not shown). 2 designates a straightener, but any form of straightener may be used. 3 shows a form of feed clutch, but any form of feed clutch

may be used. 4 shows a pair of pulleys, one loose and the other secure on shaft 5. On the opposite end of same is a crank disk 6, having a crank pin 7, upon which is movably mounted a driving rod 8. To the opposite end of said driving rod is movably secured the intermediate joint of the toggle 9. One end of the toggle is pivoted to a bracket 10, which is firmly secured to the bed 14. The opposite end of said toggle 9 is pivoted to a driving member 11, having tongues 12, adapted to travel in grooves 13, in the bed 14. A pair of rollers 15 are journaled in a cross-arm 16, which is a part of member 11. The said rollers 15 are adapted to engage the cam surfaces 17 on a pair of levers 18, the said levers 18 being pivotally secured by bolts 19 to the bed 14. Levers 18 have short arms 20 adapted to engage the free ends of rocker arms 21, which are pivotally secured to the bed 14 by bolts 21. In said rocker arms are rigidly secured shear knives 22, and grip dies 24. 25 is a bumper plate secured to member 11 with screws. The bumper plate 26 is secured in like manner to the die-carrier 27 so they may be removed when worn or battered and new ones placed in their stead. One end of the die carrier 27 is movably mounted on a standing bracket 47 by a bolt 28 and the opposite end bifurcated and made of steel of such thickness and temper as will normally hold its legs or jaws apart. The rollers 29 pivotally secured to the jaws of the die-carrier 27 are adapted to engage the cam surfaces 30 on the cheeks 31, and close the jaws of said die carrier 27, as clearly illustrated in Fig. 5. 32 designates grooves in the head-forming dies 33 and 34. 35 is a collar on the finished product. 36 designates a pair of flat springs intended to normally hold the grip dies 24, and shear knives 22 open and out of engagement with wire 1. 37 shows a pair of pins intended to limit the movement of levers 18. 38 is a flat spring intended to cause the die-carrier to retreat to its normal position (as seen in Fig. 1) on the instant in which the grip dies open and release the finished product. A pin 39 secured to a standing arm 40 which is part of member 11, is adapted to travel in a slot 41 in link 42. Slot 41 will permit pin 39 to move forward after feed clutch 3 has stopped against the pin 46, which is clearly shown in Fig. 8. The link 42 connects pin 39 with the feed clutch 3.

having fingers 43 held in engagement with the wire 1 by flat springs 44. The coil spring 45 will hold the feed clutch 3 in its normal position. 46 is a pin to limit the movement of the feed clutch 3. 47 is a standing bracket secured to the bed 14 by bolts. The upper end is duplex, so constructed as to receive the die carrier 27, which has its upper end made in the form of a yoke 48. This method is intended to prevent wobbling and carry the dies 33 and 34 very exact in their position so the work piece 23 will be sure to enter them. 49 is a standing bracket secured to the bed 14 for the purpose of supporting the feed clutch 3, which is pivotally suspended upon bolt 50. It will be understood that the dies, 33 and 34, may be removably secured in the die carrier, 27, in any convenient manner.

20 The operation of my machine is as follows: The end of a coil of wire 1 is placed in the straightener 2, through the feed clutch 3 to a position shown in Fig. 1. Power applied to pulley 4 will revolve shaft 5 which in turn will revolve crank disk 6 carrying with it crank pin 7, causing the driving rod 8 to take a downward course, taking with it the intermediate joint of toggle 9. As one end of said toggle is held by the bracket 10 the opposite end will now travel forward, carrying with it the driver 11 upon tongues 12 in grooves 13 in the bed 14. The pair of rollers 15 on cross-arm 16 engage the cam surfaces 17 on levers 18, and compel them to swing upon their bearings 19. The short arms 20 of levers 18 now bear upon the rocker arms 21 and close the shear knives 22 and sever a work piece of wire 23 from the wire 1, and make a point on it simultaneously. Before the work piece is entirely severed from the wire the corrugations on the grip dies 24 begin to cut into the work piece and hold it securely. The mechanism is so timed that the bumper plate 25 now collides with bumper plate 26 and will swing the free end of die-carrier 27 forward on its bearing 28. A pair of rollers 29 now engage the cam surfaces 30 on cheeks 31 and close the dies as seen sectionally in Fig. 5. The end of the work piece now enters the hole made by the grooves 32 in the dies 33 and 34; the dies continue until the shoulder *a* on die 33 engages the end of the work piece 23, which will upset and fill the pocket at *b*. This constitutes the head on the end of the nail. As the dies proceed forward the surplus of work piece 23 yet remaining will upset between the dies 33 and 34 and the grip dies 24 as seen in 35 in Fig. 3. This completes the formation of the nail. Crank pin 7 now begins the upward half of the circle it travels in and the opposite movement takes place in all the previously described parts except the die-carrier 27 which remains until the rollers 15 are no longer in

engagement with levers 18, then the flat springs 36 bear upon rocker arms 21 and open the grip dies 24 and release the nail. This movement swings the long arms of levers 18 toward each other until they stop against the pins 37. Immediately after the nail is released from the grip dies 24 the flat spring 38 swings the die-carrier 27 back to its normal position, as seen in Fig. 1. The rollers 29 are now no longer in engagement with cheeks 31 and the jaws of the die-carrier open the dies, and the nail falls from out the dies 33 and 34. The pin 39 on standing arm 40 is so timed that it now comes to the end of the slot 41 in link 42 and pulls it forward, bringing with it feed clutch 3. The fingers 43 held in engagement with wire 1 by flat springs 44 draw the wire into the machine the required distance to form a new work piece. The coil spring 45 will bring the feed clutch 3 back to its normal position, as seen in Fig. 3, when the driver 11 goes forward. The pin 46 is set in such position as to insure the correct length of a work piece of wire.

Because of the fact that it requires great pressure to upset the collar 35 I have placed the rocker arms 21 at an angle of about forty-five degrees from the line in which the wire 1 travels. This position will add to the pressure on the grip dies 24 beside the pressure already obtained by levers 18 as previously described, or as the pressure of the head-forming dies 33 and 34 increases upon the work piece 23, the free ends of rocker arms 21 would naturally close together, by referring to Fig. 5 it will be seen that great force will be brought upon the grip dies 24, and they will cling to the work piece 23, and will not permit it to slip. The inner sides of levers 18 stand parallel with each other while the heads are being formed on the nail, as seen in Fig. 5. This position will permit the rollers 15 to travel between said levers 18 without releasing the pressure from the grip dies 24.

I do not desire to be understood as limiting myself to any certain size, but reserve the right to vary the machine in size and strength in order to be able to make nails of any size as may be required to fill the various purposes to which this peculiar nail may be applied, without departing from the spirit of my invention as set forth in the following claims.

Having thus fully described my invention, I claim and desire to secure by Letters Patent:

1. In a nail-making machine, a bed, feeding means for advancing the stock over said bed, a heading die mounted for movement toward and from the end of the stock, a driver for said die mounted for reciprocation upon the bed, rocker arms pivoted one at either side of the path of reciprocation of

1. said driver, gripping jaws mounted for movement transversely of the path of advance of the stock, one on either side of said path, said rocker arms being each adapted at 5 one end to engage said gripper jaws, the driver and the other ends of said rocker arms being provided with co-operating cam surfaces whereby the advance of the driver toward the stock actuates the rockers to 10 cause the gripper jaws to engage said stock, and cutters carried rigidly with the respective gripper jaws for severing the stock simultaneously with its engagement by the grippers.
2. In a nail-making machine, a bed, means for advancing stock over said bed, a heading die and means for driving it against the end of the stock, a pair of gripping jaws and arms upon which they are carried, said arms 20 being pivotally mounted for swinging the jaws transversely of the path of advance of the stock, a line connecting the pivot axis of one of said arms with the center of the jaw carried by that arm making an angle of 25 about 45 degrees with said path of the stock, and the pivots of said arms being located at the opposite side of the gripper jaws from 30 the heading die.
3. In a nail-making machine, a bed, means for advancing stock over said bed, a heading die and means for driving it against the end of the stock, a pair of gripping jaws and arms upon which they are carried, said arms being pivotally mounted for swinging the 35 jaws transversely of the path of advance of the stock, a line connecting the pivot axis of one of said arms with the center of the jaw carried by that arm making an angle of about 45 degrees with said path of the 40 stock, the pivots of said arms being located at the opposite side of the gripper jaws from the heading die, and means for causing initial engagement of the gripper jaws with the stock during the advance of the 45 heading die toward the end of the stock.
4. In a nail-making machine, a heading die having a heading chamber and a cylindrical bore leading to said chamber dimensioned to accommodate the stock used for 50 nails, means for forcibly entering the end of the stock into the heading chamber of the die through the said bore thereof for forming a head on said end of the stock, said die being made in two parts adapted to be separated for releasing the headed stock.
5. In a nail-making machine, a heading die having a heading chamber and a bore leading to said chamber of cross section 55 substantially equal to that of the stock used for the nails, gripping devices for holding the stock, means adapted for causing relative movement of such gripping devices and the heading die for forcibly entering the end of the stock into the heading chamber
- through the bore of said die to form a head on said end of the stock, said relative movement being sufficient for swaging said stock into a second head immediately outside the heading die, and said die being made in two parts adapted to separate for releasing the headed stock.
6. In a nail-making machine, a heading die having a heading chamber and a bore leading to said chamber of cross section substantially equal to that of the stock used for the nails, gripper jaws and means for causing them to engage the stock, means adapted for causing relative movement of said gripper jaws and the heading die for forcibly entering the end of the stock into the heading chamber thereof through the said bore to form a head on said end of the stock, the surfaces of said gripper jaws which face the heading die extending approximately perpendicular to their gripping surfaces, and the relative movement of the gripper jaws and heading die being sufficient for swaging the stock into a head between said die and the perpendicular surfaces of said gripper jaws, the die being made in two parts adapted to separate for releasing the headed stock.
7. In a nail-making machine, a heading die having a heading chamber and a cylindrical bore leading to said chamber dimensioned to accommodate the stock used for nails, means for forcibly entering the end of the stock into the heading chamber of the die through the said bore thereof for forming a head on said end of the stock, and a die carrier comprising a bifurcated arm of spring metal, said die being made in two parts mounted on the respective prongs of said arm, and said prongs standing normally separated in position for releasing the headed stock from the die.
8. In a nail-making machine, a heading die having a heading chamber and a cylindrical bore leading to said chamber dimensioned to accommodate the stock used for nails, means for forcibly entering the end of the stock into the heading chamber of the die through the said bore thereof for forming a head on said end of the stock, said die being made in two parts adapted to be separated for releasing the headed stock, the end wall of the heading chamber being formed integrally with one of said two parts.
9. In a nail-making machine, a bed, stock gripping devices adapted for holding the stock fixed with respect to said bed, a heading die having a heading chamber and a bore leading to said chamber dimensioned to accommodate the stock used for nails, said die being mounted for movement toward and from said gripping devices, such movement being adapted for forcibly entering the end of the stock in the heading chamber of the die through the bore thereof for forming a head on said stock, said die

being made in two parts adapted to separate for releasing the headed stock, means yieldingly holding said parts separated from each other, a pair of cheeks fixed to the bed 5 at either side of the path of the heading die thereover and spaced apart to receive the two members of said die when they are closed together, and operating means adapted to engage said members of the heading die for 10 forcing them between said cheeks and on to the end of the stock.

10. A nail-making machine comprising, a bed, gripping devices adapted for holding the nail stock fixed with respect to said bed, 15 an arm pivoted to permit its free end to swing toward and from said gripping devices, said free end being bifurcated and of spring metal, a heading die having a heading chamber and a bore leading to said 20 chamber dimensioned to accommodate the nail stock, said die being made in two parts

carried, respectively, by the two prongs of the bifurcated arm, said prongs being normally positioned to separate the two parts of the die for releasing the headed stock 25 therefrom, a pair of cheeks fixed to the bed at either side of the path of swing of the bifurcated arm and spaced apart to receive its prongs when they are closed together with the two die members in contact with 30 each other, and a driver mounted for reciprocation on the bed adapted to engage the free end of the swinging arm for forcing its prongs between said cheeks and forcing the die on to the end of the stock for heading it. 35

In testimony whereof I have signed my name in the presence of two subscribed witnesses.

DAVID H. McCLELLAND.
